FRAME FOR FLEXIBLE SHEET MATERIAL

Filed Aug. 27, 1926

Inventor:
Carl R. Johnson
By Luther Johns Atty.

UNITED STATES PATENT OFFICE.

EARL R. JOHNSON, OF CHICAGO, ILLINOIS:

FRAME FOR FLEXIBLE SHEET MATERIAL.

Application filed August 27, 1926. Serial No. 131,830.

The present improvements relate to frames for holding thin and flexible sheet material containing photographs or other pictures, calendars, baseball schedules and other data. In some applications the device 5 may constitute a tag to be attached in any suitable way to baggage, parcels or other articles.

One object of the invention is to provide 10 a simple form of frame according to which sheet material of appropriate size and shape may be applied to the frame in an easy manner and be held securely therein. Another object is to provide a frame of the character 15 described according to which the area of the material exposed may be approximately that of the general area of the frame. It is an object to provide a frame which may readily be attached to some other object, for 20 example a mirror, whereby such object will have increased utility. Other objects and advantages will appear hereinafter.

In the drawings, Figure 1 is a face view 25 of a preferred form of my improved frame secured as an attachment upon the rear surface of a small hand mirror; Fig. 2 is a medial sectional view on an enlarged scale of the device of Fig. 1, as on the line 2—2 thereof; Fig. 3 is a perspective of the device 30 of Figs. 1 and 2; Fig. 4 shows the improved frame in face view in a form in which the marginal ring of a small hand mirror is formed to constitute also my improved frame; Fig. 5 is an enlarged medial 35 section of the device of Fig. 4 on the line 5—5 thereof; and Fig. 6 is an enlargement of the left end of Fig. 2. In Figs. 2 and 5 the mirror is shown in edge view.

Referring to Figs. 1, 2 and 3, my improved frame 10 designed as an attachment 40 for small pocket mirrors is preferably made of light-weight sheet metal and in a shape conforming to that of the mirror to which it is attached. Fig. 2 shows details of an ordinary pocket-mirror construction in 45 which there is a silvered glass plate 11, a piece of backing material such as cardboard 12, and a rear cover plate 13. The plate 13 is marginally turned over at 13^a to form an 50 annular crimping bead, and there is usually a narrow somewhat conical ring 14 interposed between the turned-over edge 13^a and the glass 11.

The frame 10 is a ring doubled U-shaped

in cross-section, and is shown as being open 55 interiorly through both legs of the U-shaped construction, although the ring-like seating part 15 may be continuous from side to side and cover the plate 13. This U-shaped and ring formation comprises the part 15, which 60 is continuous and rests upon the back plate 13 of the mirror, and the part 16 overlying the part 15, these parts 15 and 16 being spaced-apart to receive the flexible sheet material which it desired to hold in the frame. 65 From Fig. 1 it will be noted that two gaps 17 are cut in the outer part 16, and these gaps are opposite each other and are preferably located midway between the upper and lower ends of the mirror. These notches or 70 gaps may be closer to one end than to the other. From material originally occupying the gaps at 17 small attachment tabs or cleats 18 are formed, shown by dotted lines in Fig. 1 as extending laterally, and in Figs. 2 75 and 3 as being bent around the marginal bead 13^a. Small tabs 19 may also be partially cut from the frame part 16 and similarly bent over the bead 13^a, and the frame 80 10 is therefore held in the instance shown 85 by four metallic clips integral with the frame and bent over in holding relation to parts of the ordinary mirror construction. In Figs. 1 and 2 the area 20 may be considered to be a card having data printed 85 thereon and normally held within the frame.

Turning to Figs. 4 and 5 the construction shown comprises the circular mirror 22, a piece of backing material such as cardboard 23, a small somewhat conical ring 24 encompassing the mirror, and my improved frame 25 which in this instance utilizes some of the ordinary mirror construction, namely part of the back construction including the turned-over margin or bead 26. The bead 90 26 merges into a shoulder or seat part 27 resting upon the backing 23, and the mirror and the backing are thus strongly clamped together and a finished edge produced. To provide my improved frame in this connection the sheet-holding part 28 is offset slightly from the plane of the part 27 so as to space this part 28 from the backing 23 sufficiently to receive the desired card or sheet, and the part 28 extends inward preferably 95 to a small extent only, the interior of the frame being open. Gaps 29 are cut in the otherwise continuous flange-like overlying 100 105

part 28, which gaps are opposite each other and are located preferably midway between the top and bottom of the device, or, where the shape is circular, as illustrated, they are preferably on a diametric line.

The gaps 17 of Fig. 1 and 29 of Fig. 4 are provided to permit of the insertion of the thin and flexible sheet material to be held by the frame. To insert such a sheet, assuming that it has been cut to the desired shape and proportions, being somewhat larger than the main sight opening in the frame, the sheet is first inserted through the notches 17 or 29 so as to occupy its normal position in the frame to the full extent possible when moved through the notches in one direction. In such case approximately one-half of the sheet will then remain overlying the flanges 16 or 28, and to insert this half of the sheet 20 it is bent back upon itself as shown by the dotted lines 30 in Fig. 5 until the more forward edges of the sheet as 30 also enter the opposed notches, and this free end is then simply moved forward until the loop-shaped 25 portion of the sheet is flattened out, whereupon the sheet is entirely beneath the overlying flanges 16 or 28 and the sheet is then held normally in the frame. To remove the sheet a slender object like a hat pin is inserted 30 under the sheet from side to side at the notches and forced away from the plane of the frame, thus drawing the sheet out as a loop.

In the past it has been customary to provide such small pocket mirrors with photographs or various information data permanently applied on the back thereof, directly upon the backing plate as 13 of Fig. 2, and experience has demonstrated that such 35 a small pocket mirror is peculiarly appropriate as a carrier for such photographs or data. When the data, such as baseball schedules, or a calendar, becomes obsolete, or the photograph appearing thereon is no longer 40 of sufficient interest, the mirror as a whole is usually discarded. According to the present improvements the usefulness of the mirror as a pocket piece may be extended indefinitely, since the frame feature of it provides 45 means for changing the subject matter carried as may be desirable from time to time.

An important feature of the invention is in the fact that the card or sheet is held with unusual security and may be removed only 50 by deliberately tearing or by withdrawal in the manner indicated, and the danger of ac-

cidental loss from the frame is entirely overcome.

Such a frame may conveniently be used as a tag for identifying parcels, hand baggage, etc., and may be secured by clips such as 18 and 19 directly upon the article to be marked, or in any other approved way. It may be used also in suitable sizes for holding photographs or other data in other connec- 65

I contemplate as being included in the present invention such changes and departures from what is thus specifically illustrated and described as fall within the scope 70 of the appended claims.

I claim:

1. A frame of the character described of rounded contour in face view, being in ring-like form, and having means for holding a 75 flexible card or sheet normally within the frame, said means comprising inner retaining means for the card or sheet and a part forming narrow outer flange-like retaining means for the card or sheet, said outer retaining means having a pair of opposed gaps therein through which the card or sheet may be inserted in the manner described, said gaps being in substantially the longest lines parallel to each other terminating in opposite sides of the frame. 80

2. A frame of the character described formed of thin sheet material, being in ring-like form, and having means for holding a 90 flexible card or sheet normally within the frame, said means comprising inner retaining means for the card or sheet and a part forming narrow outer flange-like retaining means having a pair of opposed gaps therein substantially midway between opposite ends 95 of the frame and through which the flexible card or sheet may be inserted in the manner described, and means integral with the frame for holding the frame as an attachment upon another object. 100

3. A combined mirror and sheet-holder of the character described comprising a mirror, a frame encompassing the marginal edges of the mirror, and means for retaining a sheet of thin and flexible material carried by said mirror frame and comprising narrow flange-like parts normally overlying edge portions of the sheet, said flange like parts having opposed gaps therein to provide entrance for such sheet beneath the flange-like parts.

EARL R. JOHNSON.
